UNITED STATES PATENT OFFICE.

JOHN CAMERON GRANT, OF BARNES, LONDON, ENGLAND.

TYPEWRITING-MACHINE FOR CODING AND DECODING MESSAGES.

1,356,277.

Specification of Letters Patent. Patented Oct. 19, 1920.

Application filed February 4, 1919. Serial No. 274,935.

To all whom it may concern:

Be it known that I, JOHN CAMERON GRANT, a subject of the King of Great Britain and Ireland, and residing at Holly 5 Lodge, 29, The Terrace, Barnes, in the county of London, England, have invented certain new and useful Improvements in Typewriting-Machines for Coding and Decoding Messages, of which the following is 10 a specification.

My invention relates to typewriters and has for its object the typewriting of a message in code, produced by consecutively depressing the keys corresponding to the lettering of the message to be coded.

The invention relates particularly to that form of code in which a key or code number of one or more figures is repeated indefinitely in relation to the consecutive letters 20 composing the original message each of which is advanced or retarded in alphabetical sequence by the number of letters given by the relative figure of the key or code number. Similarly in decoding the message received, the key or code number is repeated 25 indefinitely in relation to the consecutive letters composing the coded message, each of which is retarded or advanced in alphabetical sequence by the number of letters given by the relative figure of the key or code number.

It has been proposed in a cryptographic machine to mount on a common shaft two type cylinders, one of which is angularly 35 adjustable on the shaft by means of a special key, and may also be constituted by a number of relatively adjustable disks to vary the code.

It has also been proposed that the typewriting machine should produce simultaneously by the same key-depression a character of the original message and the corresponding character of the coded message.

The present invention consists in means 45 for the simultaneous production of the original and coded message letter by letter for each key-depression from a series of disks or shuttles, on a common axis, one set relatively fixed in relation to the axis and the 50 other set relatively adjustable in relation to the zero position and to each other, both sets or the latter set only being shifted axially at each key depression; also for simultaneously transcribing and decoding 55 the message by the same means the machine

being set appropriately to obtain the desired result.

The invention further consists of a method of forming type-wheels or shuttles with a castellated or multiple splined hole 60 or with notches and drilled holes for affording means for setting the parts in position relatively to each other and for driving them when so set.

The invention further consists in the provision of a type-wheel shaft or tube having the appropriate number of splines or castellations or a single driving arm or rib capable of engaging with the required notches in the respective type shuttles.

Whether a splined shaft is used in combination with type cylinders as in the adaptation of the invention to a machine of the Blickensderfer class or whether the motion of the type wheels is one of rotation through 75 varying angles always in the same direction or sometimes in one direction and sometimes in the other, or whether type shuttles are used as in typewriting machines of the Hammond class the action is virtually the same 80 and it is therefore only necessary to describe the application to the latter class of typewriting machine.

The invention also consists in the improved cryptographic typewriting machine 85 hereinafter described.

In the accompanying drawings, which illustrate one method of carrying my invention into effect:

Figure 1 is a central section from front 90 to back of the complete machine;

Fig. 2 is a detail view of the hammer operating mechanism;

Fig. 3 is a developed view of the printing surfaces;

Fig. 4 is a fragmentary plan view showing the relative positions of certain main parts;

Fig. 5 is a detail view showing the method of fixing the various rows of type in their relative positions;

Fig. 6 is a detail view showing a slightly modified form of construction.

The form of machine shown is of the general type in which the characters from which printing is made are carried on a 105 cylinder which is rotated at each key depression in order to bring any desired letter to the printing position, printing being then effected by the operation of a hammer situated behind the paper. In such a machine 110

the letter keys 1 are pivoted at a point 2 located at some distance from each end of the key lever.

It is to be observed that in using the term 5 "letter keys" in the description and claims, I include keys which are used to print numerals, signs or any other character, the term "letter key" being used in contradistinction to the ordinary spacing or shift- 10 keys and to a special key hereinafter referred to.

Located above the inner ends of the keys 1 is a frame 3 through which project a number of pins 4 the lower end of each of 15 which rests on one of the keys. The effect, therefore, of depressing one of the keys is, as indicated, to raise the corresponding pin 4 against the action of a spring 5 surrounding it, thus causing the upper end of the 20 pin to project through a portion of the framework 6 in which it is free to slide.

Situated in front of the pins 4, which in 25 the machine described are disposed approximately in a semi-circle, as indicated in Fig. 4, is a lever 7 fixed to the spindle 8. A second lever 9, also fixed to this spindle abuts at its upper end against a bearing surface on the hub 10 which is free to revolve around the spindle 11.

30 It is to be understood that the lever system 7, 8 and 9 is duplicated on the opposite side of the machine, that is to say the lever 7 shown in Fig. 1 rests on the keys to the right of the central plane of 35 the machine and a corresponding lever 7 rests on those to the left of the central plane which, of course, do not appear in Fig. 1. The upper ends of the two levers 9, however, are both shown in Fig. 4.

40 Attached to the hub 10 is a stop-lever 12 of such a length that its end passes over the tops of the pins 4 but is arrested by any one of these pins which is in the raised position. It will be seen, therefore, that 45 depression of any letter key 1 will cause motion of the stop-lever 12 the extent of which will depend upon which of the pins 4 is raised, that is to say upon which letter key has been depressed.

50 Attached to the stop-lever 12 is a driving member or rib 13 which projects upward within two cylindrical anvils 14, 15, and engages the printing shuttles 16, 17 in the manner hereinafter described.

55 Printing is effected by means of a hammer 18 which is operated by the following mechanism:—

Situated within the pins 4 is a lever 19 fixed on a spindle 20 and resting on the inner ends of the letter keys 1. It is to be understood that the lever 19 is duplicated in a similar manner to the lever 7, both of these levers 19 being fixed to a spindle 20 common to them. On depression of one 65 of the letter keys the forward end of the

lever 19 is raised, as indicated, resulting in the rocking of a lever 21 upon which the inner end of the lever 19 rests and which is pivoted at 22. (See Figs. 1 and 2.) This lever 21 has two other arms 23, 24, the former of which engages by means of a pin and slot with a pawl 25 hinged at 26 to a lever 27 pivoted at 28. Also pivoted at 28 is a ratchet wheel 29 fast on the same spindle as a gear wheel 30 which engages 75 a rack 31 attached to the paper carriage, this rack being under the influence of a spring drum 32 which tends to impel it from right to left, as viewed from the front of the machine, in the well known manner. 80 This motion is prevented by the pawl 25, but it will be seen that if the arm 23 be rocked as a result of depression of one of the keys 1 the pawl 25 will be withdrawn from engagement with the ratchet wheel 85 29 and the latter will be free to rotate in a clockwise direction. This motion, however, is still prevented by the engagement of a projection 33 on the arm 24 with one of the ratchet teeth. The hammer 18 is 90 pivoted at 34 and is provided with an extension 35 to which a tension spring 36 is attached which tends to move the hammer toward the anvils 14 and 15. So long, however, as the pawl 25 engages with the 95 ratchet wheel 29 this motion is prevented on account of the arm 27 being pivoted to the hammer 18 at 37. When, however, the pawl 25 is disengaged from the ratchet wheel 29 the hammer moves forward to effect the printing operation under the action of a spring 36. On release of the letter key 1 the lever 21 returns to its original position under the action of the spring 38, thus bringing the projection 33 clear of 100 the ratchet wheel 29 which is therefore free to rotate and allow movement of the paper carriage. This movement, however, is limited to the distance occupied by a single printed letter on account of the fact 105 that the pawl 25 is reengaged with the ratchet wheel 29 by the arm 23.

The two printing shuttles 16 and 17 mounted upon separate anvils 14 and 15 are necessary in order that the message 110 may be printed simultaneously in plain characters and in cipher. For this purpose the type shuttle 16 consists, as indicated in Fig. 3, of four complete rows of type characters each row being exactly similar to 115 the others and the positions of the rows being fixed relatively to each other.

The type shuttle 17 also consists of four rows in each of which the characters are the same and arranged in the same order 120 as in the case of the shuttle 16. Each row is, however, adjustable in a longitudinal direction relatively to the other row and to the rows of the shuttle 16.

Since it is required, as hereinafter set forth, 130

that any of the rows of the shuttle 17 may be moved a definite number of spaces, for example ten, on either side of the normal position, it is necessary that this number of letters be repeated at each end of each of the rows, as indicated in Fig. 3, in order that printing may occur in whatever position the rows are set. These shuttles 16 and 17 both engage the driving member or rib 13 and are thereby rotated around their respective cylindrical anvils 14 and 15. To this end the shuttle 16 and each of the rows of the shuttle 17 is formed with an inwardly projecting flange 39 which extends through a corresponding slot 40 in the anvil. In the case of the shuttle 16, this flange is formed with a notch through which the rib 13 passes in such a manner that the shuttle rotates with the rib but is capable of moving relatively to it in an axial direction. The flange attached to each row of the shuttle 17 is formed with a number of such notches 41 in order that engagement with the rib 13 may be effected in whatever position the rows may be adjusted. The rib thus serves to connect all the rows together so that they will rotate as one whole. They are, however, further secured together by means of a fork 42, Fig. 5, which may be passed through a series of holes 43 drilled in the flanges 39. The spindle 11 to which the anvils 14 and 15 are fixed rests upon a cam 44 mounted upon a spindle 45 to which is also fixed a ratchet wheel 46. This ratchet wheel 35 is engaged by a pawl 47 carried by a key 48 pivoted at 49 and is also engaged by a spring detent 50 which prevents its rotation in a clockwise direction. The cam 44, ratchet wheel 46, and key 48 are so proportioned that a single depression of the key will cause the spindle 11, which is so mounted as to be free to move axially, to rise a distance corresponding to the height between any two rows of type on either of 45 the shuttles 16 or 17. Furthermore, the cam is so shaped that after it has raised the spindle 11 to such an extent that the lowest row of type in each shuttle is opposite the printing position a further depression of the 50 key 48 causes the spindle to be lowered so as to bring the highest row of type into the printing position, the action of the cam to bring successive rows into the printing position being then repeated.

55 In order to print simultaneously from the shuttles 16 and 17, the hammer 18 is formed with two striking surfaces 51 and 52, these being arranged to strike the paper 53 with equal pressure through rubber strips 54, 55 in the well known manner.

The paper 53 which receives the message printed both in plain characters and in cipher is passed between feed rollers 56, 57, over idle rollers 58, 59 and 60, and between feed rollers 61, 62. The feed rollers 56 and

61 are geared together, as indicated, by a chain 63 or in any other suitable manner so that the paper 53 shall be fed at the same rate between each pair of rollers and be thus maintained in a taut condition. 70

The paper is led around the idle roller 59, which is preferably detachable to facilitate insertion of the paper, in order that sufficient space shall occur between the plain and cipher messages to allow of a reasonable 75 length in the former.

Separate ink ribbons 64, 65, are provided for printing the plain and cipher messages respectively, four spools 66 being, as indicated in Figs. 1 and 4, necessary for these 80 ribbons. These spools are mounted in pairs on spindles 67 which are geared by worm and worm wheel mechanism to spindles 68 driven by a ratchet and pawl mechanism 69 from the levers 19. The machine is operated as follows:—

Having selected a code number, such as 1327, the rows of the shuttle 17 are respectively displaced from their central position by the number of spaces indicated by the 90 digits of the code number. For instance, the developed view of the type surfaces shown in Fig. 3 indicates the setting of the shuttle 17 corresponding to the code number 1327, and it will be seen that the top 95 row of type is shifted one space to the left, the second row three spaces, the third row two spaces and the fourth row seven spaces. The character, therefore, which is printed by the shuttle 17 to correspond to a given 100 character on the shuttle 16, which is of course the same as that shown on the key lever, is the one occurring one, three, two or seven spaces lower down the alphabet according as printing is taking place from 105 the first, second, third or fourth row.

As above described, change from one row to another is brought about by depression of the key 48, or if it be desired that this change shall take place after each depression 110 of one of the letter keys 1, the lever 48 instead of being made as a separate key is formed with an extension bent at right angles so as to extend underneath all the letter keys 1, whereby depression of one of 115 these keys involves operation of the lever 48 and therefore change from one row to the next of the type shuttle 17.

The retention of the key 48 permits the message to be broken up into groups of letters of any desired length according to the conditions of sending; the spacing may follow the original message or if the message is intended to be telegraphed it may be divided into groups of five letters or whatever 125 other number may be suited to the conditions governing telegraphic communication.

It is of course possible to use five or more adjustable shuttles and a corresponding number of alphabets on the relatively fixed 130

shuttle so that the typewriter can be used for coding and decoding messages in which the key number consists of five or more figures.

By the arrangement adopted it is possible 5 to advance or retire the letters of each shuttle for nine positions in each direction, giving a total of $(18 \times 18 \times 18 \times 18)$ or over 100,000 combinations and it is possible to indicate that any figures of the code number 10 are to be taken in the reverse direction by overscoring such figures in the note taken of the key number, thus 4285 would mean that the first shuttle was set 4 forward, the second 2 backward and so on.

15 In the slightly modified construction illustrated in Fig. 6, the anvil 14 is made stationary, being carried by an arm 70 fixed to the frame 6 instead of by the spindle 11. Only the anvil 15, therefore, receives axial motion from the cam 44, but a rotational motion is imparted to the shuttle 16 as before by the driving member 13. In this case it is obviously necessary to have only one row of type, as indicated, on the shuttle 16, the 20 shuttle 17 having four adjustable rows, as in the construction previously described.

Having now described my invention, what I claim as new and desire to secure by Letters Patent is:—

30 1. In a cryptographic typewriter for simultaneously printing the original and cipher messages the combination of two sets of printing surfaces, one for printing the original message and the other for printing the cipher message, the latter surface being composed of a number of similar rows of type longitudinally adjustable relatively to each other and to the first-mentioned surface, means for bringing said rows successively and always in the same order into operative 35 position for printing, a series of letter keys, means under the control of the letter keys for simultaneously moving the printing surfaces from the normal position in order to bring the desired corresponding letters to the printing position, a single sheet of paper 40 on which both the original and cipher messages are printed, and a hammer and operating means therefor adapted to print simultaneously from both surfaces at each letter key depression.

45 2. In a cryptographic typewriter as set forth in claim 1, two cylindrical anvils at least one of which is movable axially, a shuttle carrying the printing surface and mounted to rotate around each anvil, a driving member connecting the shuttles, and means operated by the letter keys for rotating the driving member through an arc 50 corresponding to the particular key depressed.

3. In a cryptographic typewriter as set forth in claim 2, a spindle upon which at least one of the cylindrical anvils is rigidly fixed, a supporting cam for said spindle 65 mounted upon a shaft, a ratchet wheel upon said shaft, a co-acting pawl carried by a lever whereby at each depression of the lever the spindle is raised a distance corresponding to that between the rows of type 70 and is finally brought from its highest to its lowest position, substantially as described.

4. In a cryptographic typewriter as set forth in claims 2 and 3 providing the same 75 number of rows of type on each shuttle, and fixing both anvils to the spindle in order to impart to them equal axial motion, substantially as described.

5. In a cryptographic typewriter as set 80 forth in claim 2, a cipher printing shuttle in which the rows of type are made separately, a flange on each row projecting through a slot in the anvil, a series of apertures in each flange spaced correspondingly to the type characters and adapted to engage means whereby the flanges are rigidly connected together, and also to engage the driving member, substantially as described.

90 6. In a cryptographic typewriter as set forth in claim 1, mounting on the hammer two striking surfaces respectively located opposite the two sets of printing surfaces in order to print simultaneously from both 95 printing surfaces.

7. In a cryptographic typewriter as set forth in claim 1 feed rollers to pass the paper on which the records are made across each printing surface, said feed rollers being 100 geared together in order to produce the same rate of feed over each surface, and to keep the paper between the surfaces in a taut condition.

8. In a cryptographic typewriter as set 105 forth in claim 1, the arrangement of a number of idle rollers over which the paper on which the records are made is passed in order to provide a space between the impressions made by the two printing surfaces.

110 9. In a cryptographic typewriter as set forth in claim 1, an inking ribbon for each printing surface, a winding-on spool and a winding-off spool for each ribbon, a spindle to carry both winding-on spools, a second spindle to carry both winding-off spools, and means operated by each letter key depression for imparting a small angular movement to at least one of the spindles.

115 In testimony whereof I have signed my name to this specification.

JOHN CAMERON GRANT.
